LINT CLEARER FOR FILLING STOP MOTIONS

Application filed March 24, 1928. Serial No. 264,403.

This invention relates to improvements in devices for insuring proper operation of filling stop motions by removing therefrom any lint which may collect during the operation of the loom.

In certain filling stop motions, particularly those on broad looms where the fork is located at the center of the loom, the lay is provided with a well or depression into which the tines 5 of the filling fork pass when weft is absent. When weft is present the fork is held up and is prevented from moving into the well at that point in the beatup of the lay where indication to stop because of weft failure may 10 occur. When weaving with certain kinds of yarn it is found that lint collects in the well and supports the fork, having the effect of permitting continued operation of the loom even though the weft be absent, because of the 15 fact that the fork is not permitted to drop into the well. It is an important object of my present invention to provide means for clearing the well of such lint as may collect and thereby insure proper operation of the 20 stop motion.

One form of center filling stop motion which has gone into general use employs a 25 fixed bracket extending rearwardly from the breast beam and having a cam face along 30 which moves a portion of the stop motion mechanism which is mounted on the lay. It is a further object of my present invention to mount a clearing device on the lay to be moved back and forth with the latter and to derive 35 its motion partly from structure carried by the bracket.

In one form my invention employs a hooked member which moves back and forth in the well of the filling stop motion in a direction 40 transverse of the lay so as to draw line forwardly. It is a further object of my invention to associate with the hooked member retaining devices located in the well and operative to prevent movement of the lint to the 45 rear part of the well after it has been moved forwardly by the hooked member.

With these and other objects in view which 50 will appear as the description proceeds, my invention resides in the combination and ar-

rangement of parts hereinafter described and set forth in the claims.

In the accompanying drawings, wherein I have shown a convenient embodiment of my invention,

Fig. 1 is a vertical section through a portion of the loom showing a filling stop motion having my invention applied thereto,

Fig. 2 is a top plan view taken in the direction of arrow 2, Fig. 1,

Fig. 3 is a detailed vertical section on line 3-3 of Fig. 2 showing the manner of operating my invention, and

Fig. 4 is a detailed vertical section on line 4-4 of Fig. 1.

Referring to the drawings, I have shown a loom frame 10 and a lay 11 to be moved toward and from the frame each beat of the loom. Secured to the breast beam 10 of the loom frame is a bracket 12 having a lever 13 pivoted thereto as at 14. By means of mechanism not shown the lever is held normally in the position shown in Fig. 1. An adjustable cam plate 15 is held by a bolt 16 to the bracket and is so placed as to expose the upper rear end of the lever 13 as clearly shown in Fig. 1.

The lay is provided with a bracket 17 to which is pivoted as at 18 a dagger carrier 19 which supports the dagger 20. An upwardly extending link 21 pivotally connected at the lower end thereof to the carrier is attached at the upper end thereof to an arm 22 of a rocking fork member 23. Said member is provided with tines 24 which extend into the well 25 in the upper forward portion of the lay 11. The lay may be provided with the usual race plate 26 and may have a backstay 27 to position the reed 28.

When the lay is in rear position the dagger 20 is held in raised position on the cam plate 15 and the effect of this is to raise the tines 24 to the dotted line position shown in Fig. 1. As the lay moves forwardly the dagger will start to move down the forwardly inclined face of the cam plate, but if weft is present the tines 24 and therefore the dagger will be held in relatively raised position so that said dagger moves forwardly over lever 13. Should weft be absent, however, the

tines 24 will move downwardly into the well to permit the dagger 20 to have direct engagement with the lever 13. Continued forward movement of the lay will thereafter effect stoppage of the loom by mechanism not shown but set into action by the rocking of lever 13 around the axis 14.

I have shown herein only sufficient structure to indicate the manner in which my invention may be used and portions of the filling stop motion have been omitted for the sake of clearness. The matter thus far described forms no part of my present invention and may be of the usual construction, references being made to Patents Nos. 560,036 10 to Hutchins and 1,369,417 to Gagnon for a more complete disclosure of the structure and operation of the particular form of filling stop motion illustrated.

In carrying my present invention into effect I provide means for clearing the well 25 of any lint which may accumulate therein. Accordingly, I provide a stud 30 which is mounted on bracket 17 to move with the lay and mount on said stud a lever 31 having an upwardly extended arm 32 located preferably in front of the lay. To the upper end of said arm 32 I pivot a plurality of clearing members 33 the rear of each of which is formed with a hook 34. The members 33 lie below the member 24 so as not to interfere with the operation of said member or the upright link 21.

The lever 31 is provided with a rearwardly extending arm 35 which extends through an eye 36 formed as part of the bracket 12 as shown more clearly in Fig. 4. The rear end of the arm 35 is weighted as at 37 if desired, although I may dispense with the weight in view of the fact that the end 35 extends through the closed eye 36 and is therefore given positive motions in opposite directions.

The hooked members 33 normally lie in the bottom of the well in the position shown in full lines in Fig. 3 when the lay is in its rearward position, or in the position shown in dotted lines in Fig. 1. As the lay moves forwardly its position will change with respect to the eye member 36 and the rearwardly extending arm 35 of the lever 31 will be raised relatively to the stud 30 to produce a left hand movement as viewed in Fig. 1 on the part of lever 31 around its supporting stud. The effect of this is to move the upright arm 32 forwardly to move the hooks from the position shown in Fig. 3 to the position shown in full lines in Fig. 1. Said hooks are therefore effective to carry forwardly any mass of lint L such as that indicated in Fig. 3.

In order to retain the lint or other accumulation in the forward position of the well I may provide the bottom of the well with a plurality of upwardly and forwardly projected pins or peg members 40 located be-

tween and on the sides of the hooked members 33. These peg members operate to prevent the lint from moving rearwardly when the hooked members 33 move back into the well upon rearward movement of the lay.

70

As shown in Fig. 3 there is an open space below the member 23 defined by the ears 41 and 42 which afford pivotal support for said member 23 and are mounted on the lay. In this way there is provided a suitable discharge opening at the forward end of the well 25 for removal of the lint.

75

From the foregoing it will be seen that I have provided a very simple device which is movable back and forth in the well 25 to engage any lint or other accumulation which may collect in said well. It will further be seen that the movement of the lint removing element is effected by the forward and backward movement of the lay and that said hooked members are in forward position where they cannot interfere with the operation of the filling fork at that time in the cycle of the loom when the filling fork will move downwardly in its normal operation. It will also be seen that the peg members extending upwardly from the bottom of the well act not only to retain the lint but also because of the fact that they are inclined forwardly aid in the discharge of the lint. Furthermore, it will be noted that the supporting structure for the filling fork carrying member 23 is provided with an opening at the forward end of the well 25 through which the lint may pass.

85

Having thus described my invention it will be apparent that changes and modifications may be made therein by those skilled in the art without departing from the spirit and scope of the invention and I do not wish to be limited to the details herein disclosed, but what I claim is:

100

1. In a lint clearing device for a filling stop motion for a loom having a lay provided with a transverse well in the upper portion thereof into which the tines of a detecting filling fork move by a downward motion to assume a horizontal position, means movable back and forth in the well below the tines when the latter are supported by filling to clear said well of objectionable accumulations, and mechanism operated by the back and forth motion of the lay to move said means.

105

2. In a lint clearing device for a filling stop motion for a loom having a lay provided with a transverse well in the upper surface toward which the tines of a detecting filling fork move to assume a horizontal position, a well clearer movable back and forth in said well in a direction parallel and below the upper surface of the lay, and mechanism operatively connected to said well and supported by the lay and deriving movement from the latter as the same moves backwardly and for-

110

115

130

wardly to reciprocate the means in the well.

3. In a lint clearing device for a filling stop motion for a loom having a lay provided with a horizontal transverse well in the upper surface toward which the tines of a detecting filling fork move to assume a horizontal position, a well clearer to be reciprocated back and forth in the well horizontally and below the upper surface of the lay to remove objectionable accumulations, and mechanism to give said means a forward movement when the lay is in its forward position.

4. In a lint clearing device for a filling stop motion for a loom having a lay provided with a horizontal transverse well in the upper portion thereof into which the tines of a detecting filling fork extend, well clearing means located in the well and movable in said well along a line out of the path of movement of the shuttle across the lay to remove objectionable accumulations from the well, and mechanism deriving motion from the lay and operatively connected to said means to move the latter out of the well at that point in the cycle of the loom when the tines of the filling fork tend to move into the cell when detecting for weft.

5. In a lint clearing device for a filling stop motion for a loom having a lay provided with a horizontal transverse well in the upper portion thereof into which the tines of a detecting filling fork extend, well clearing means to be movable horizontally in said well and below the upper portion of the lay to engage and remove objectionable accumulations, and mechanism supported by the lay and deriving movement from the lay and operatively connected to said means to move the latter forwardly when the lay is moving forwardly.

6. In a lint clearing device for a filling stop motion for a loom having a lay provided with a transverse well in the upper portion thereof into which the tines of a detecting filling fork extend, well clearing means to be movable horizontally in the well and in a line out of the path of movement of a shuttle across the lay to engage and remove objectionable accumulations, mechanism mounted on and moving with the lay and operatively connected to the means, and a fixed guide for said mechanism to cause operative movement of the mechanism as the lay moves forwardly, whereby as said lay moves the well clearing means also moves.

7. In a lint clearing device for a filling stop motion for a loom having a lay provided with a transverse well in the upper portion thereof into which the tines of a detecting filling fork extend, well clearing means to be movable in the well to engage and remove objectionable accumulations, a lever operatively connected to the means and pivotally mounted on the lay, and a relatively fixed member to cause movement of the lever as the

lay moves back and forth, whereby the means is moved in the well relatively to the lay by motion derived from the lay.

8. In a lint clearing device for a filling stop motion for a loom having a lay provided with a transverse well in the upper portion thereof into which the tines of a detecting filling fork extend, well clearing means to be movable in the well to engage and remove objectionable accumulations, a lever pivoted to the lay and operatively connected to the means, and a fixed member forming part of the filling stop motion to engage a portion of the lever to cause movement of the latter on the pivot thereof as the lay moves back and forth, whereby the means is caused to move in the well relatively to the lay.

9. In a lint clearing device for a filling stop motion for a loom having a lay provided with a transverse well in the upper portion thereof into which the tines of a detecting filling fork extend, well clearing means to be movable in the well to engage and remove objectionable accumulations, a lever pivotally mounted on the lay and having an arm oblique with respect to the path of movement of the lay, and fixed structure to engage said arm of the lever to cause rocking movement of the lever as the lay moves, said mechanism being operatively connected to the means to cause movement of the latter as the lay moves.

10. In a lint clearing device for a filling stop motion for a loom having a lay provided with a transverse well in the upper portion thereof into which the tines of a detecting filling fork extend, well clearing means to be movable in the well to engage and remove objectionable accumulations, a lever pivotally mounted on the lay and having a rearwardly and downwardly extending arm, and a fixed element to have engagement with said arm to cause rocking movement of the lever as the lay moves forwardly, said mechanism being connected to the means to move the latter forwardly as the lay moves forwardly.

11. In a lint clearing device for a filling stop motion for a loom having a lay provided with a transverse well in the upper portion thereof into which the tines of a detecting filling fork extend, well clearing means to be movable in the well to engage and remove objectionable accumulations, a fixed device including a closed eye, and a lever pivotally mounted to the lay and having an arm oblique with respect to the path of the movement of the lay and extending through the eye, said eye causing rocking movement of the lever positively in two directions as the lay moves back and forth, said mechanism being operatively connected to the means to cause the latter to reciprocate in the well.

12. In a lint clearing device for a filling stop motion for a loom having a lay provided with a transverse well in the upper portion thereof into which the tines of a detecting

filling fork extend, means movable back and forth in the well to clear the same of objectionable accumulations, mechanism operative by the back and forth motion of the lay to move said means, and retaining means in the well to hold any accumulations which may be moved forwardly by the clearer.

13. In a lint clearing device for a filling stop motion for a loom having a lay provided with a transverse well in the upper portion thereof into which the tines of a detecting filling fork extend, means movable back and forth in the well to clear the same of objectionable accumulations, mechanism operative by the back and forth motion of the lay to move said means, and means defining forwardly and upwardly extending pegs secured in the bottom of the well to engage and retain and prevent retrograde movement of any accumulations which may be moved into holding position with respect to said pegs by the means.

14. In a lint clearing device for a filling stop motion for a loom having a lay provided with a transverse well in the upper portion thereof into which the tines of a detecting filling fork extend, a bracket carried by the lay and having two spaced members to afford support for the filling fork, the space between said members aligning with the well in the lay, and means movable in the well to move objectionable accumulations forwardly in the well and discharge the same through the space between the members.

15. In a lint clearing device for a filling stop motion for a loom having a lay provided with a transverse well in the upper portion thereof into which the tines of a detecting filling fork extend, a bracket carried by the lay and having two spaced members to afford support for the filling fork, the space between said members aligning with the well in the lay, and means movable in the well to move objectionable accumulations forwardly in the well and discharge the same through the space between the members, said means extending from a position in front of the lay between said members and into the well.

16. In a lint clearing device for a filling stop motion for a loom with a lay having a horizontal transverse well in the upper surface thereof and a filling fork movable downwardly toward the well and adapted to enter the well when filling is absent but prevented from entering the well when filling is present, a clearing device movable horizontally in the well and actuated by the forward stroke of the lay to remove objectionable accumulations from the well and out of the path of the filling fork.

17. In a lint clearing device for a filling stop motion for a loom with a lay having a horizontal transverse well in the upper surface thereof and a filling fork movable down-

wardly toward the well and adapted to enter the well when filling is absent but prevented from entering the well when filling is present, a clearing device movable horizontally in the well to remove objectionable accumulations from the well and out of the path of the filling fork.

18. In a lint clearing device for a filling stop motion for a loom with a lay having a horizontal transverse well in the upper surface thereof and a filling fork movable downwardly toward the well and adapted to enter the well when filling is absent but prevented from entering the well when filling is present, a lint clearer located in the well, and means to move said clearer forwardly to remove objectionable accumulations of lint from the path of movement of the fork into the well.

In testimony whereof I have hereunto affixed my signature.

ALBERT A. GORDON.
